UNITED STATES PATENT OFFICE

171,633

SPOON

Jose Barata y Barrera and Ralph W. Krewson,
Baltimore, Md., assignors to The Stieff Company,
Baltimore, Md., a corporation of Maryland

Application May 7, 1953, Serial No. 24,913

Term of patent 14 years

(Cl. D54—12)

To all whom it may concern:

Be it known that we, Jose Barata y Barrera and Ralph W. Krewson, respectively a citizen of Spain and a citizen of the United States, both residing at Baltimore, Maryland, have invented a new, original, and ornamental Design for a Spoon, of which the following is a specification, reference being had to the accompanying drawing, forming part thereof.

The figure is a top plan view of a spoon showing our design.

The back of the spoon is substantially plain.

We claim:

The ornamental design for a spoon, as shown and described.

JOSE BARATA Y BARRERA.
RALPH W. KREWSON.
